[57] **CLAIM**

The original design for a mold tube receiving attachment for a hearing aid, substantially as shown and described.

DESCRIPTION

FIG. 1 is a side elevation of a mold tube receiving attachment for a hearing aid showing my new design, the opposite side being a mirror image thereof;

FIG. 2 is a view of the said attachment as seen from the left of its FIG. 1 position;

FIG. 3 is a view of said attachment as seen from the right of its FIG. 1 position; and

FIG. 4 is a top plan view thereof.

FIG. 1.

FIG. 2.

FIG. 4.

FIG. 3.
